DRAFT REGULATOR

Clarence A. Crooker, Mankato, Minn.

Application May 27, 1943, Serial No. 488,679

2 Claims. (Cl. 236—45)

This invention relates to draft control devices. In my prior Patent Number 2,252,425, granted August 12, 1941, I disclosed a bearing construction for the pivot means for a valve in a draft control device. This pivot element included a U-shaped piece of metal bolted or otherwise secured to the rim of the draft control device with an aperture through one leg of the U-shaped piece to receive the pivot pin, the other leg being solid to restrain the pin against longitudinal movement and provide a bearing surface.

One of the objects of the present invention is to provide pivot means for the valve member in the draft control device wherein the bearing member is formed integrally from the material of the rim thus considerably simplifying manufacture assembly work.

Another object of the invention is to provide a draft control device for use on the end of a short pipe section which is outwardly flanged wherein means for slidably engaging the flange of the pipe section is stamped or struck from the metal of the rim of the regulator in a manner similar to the tongues struck from the rim to provide the valve bearing elements.

A further object of the invention is to greatly simplify the construction of a draft regulator by reducing the number of parts to a minimum namely a rim, a valve, and a pivot member for the valve.

These and other objects and advantages of the invention will more fully appear from the following description made in connection with the accompanying drawing, wherein like reference characters refer to the same parts throughout the views, and, in which:

Fig. 1 is a side elevation of a portion of a flue with a lateral branch section and my regulator thereon, a portion of the branch being broken away and the regulator being shown in section with an alternate position of the valve in dotted lines;

Fig. 2 is a front elevation of a regulator mounted on a flue;

Fig. 3 is a top view of the regulator showing it mounted on a short section of pipe;

Fig. 4 is a front elevation of a modified form of the device; and

Fig. 5 is a side view thereof.

In the drawing there is shown a vertical flue section 6 having a short T section 7 extending outwardly therefrom. The outer end of the T section 7 is provided with an outwardly directed flange 8.

The regulator includes a rim 9 which is an-

nular and flat with a relatively large central opening. At spaced points about the rim tongues 10 are struck from the metal of the rim and as shown their free ends are directed radially inwardly to the center of the rim 9. It should further be noted that the tongues 10 extend outwardly from the main body of the rim at a rather abrupt angle and thence radially inwardly in spaced relation to the back of the rim so that the main body of the rim will lie against the surface of the short pipe section, and the inner or the free ends of the tongues will lie behind the flange 8. The rim is thereby supported on the flange 8 and slidably rotatable thereon. Due to the fact that the rim 9 is flat and made of sheet metal it can be sprung slightly so that the tongues 10 can be slipped behind the flange 8 on the short pipe section 7. This affords an extremely simple and economical means for rotatably mounting a regulator rim on a flanged piece of smoke pipe. Preferably located above the horizontal center line of the rim 9 is a pair of tongues 11 and 12. Similar tongues are disposed on the opposite side of the rim as best shown in Figs. 2 and 3. The tongues 12 are provided with tapered apertures 13 to receive the ends of a pivot rod or pin 14. The rod 14 extends through the tongues 12 and is of a length approximately the same as the distance between the inner faces of the outer tongues 11. The ends of the rod 14 are preferably pointed as shown in Fig. 3 so that there is little frictional contact between the rod 14 and the tongues 11. Friction is reduced also by the tapering of the apertures 13 in the tongues 12 and there is no pocket or other collecting place for soot and dirt which might interfere with proper movement of the pivot rod 14 in the bearing tongues 11 and 12. A valve member 15 is positioned in the aperture provided by the rim 9, and said valve member, as shown in Fig. 2, is preferably of slightly less diameter than the inner edge of said rim 9. The valve member 15 has a pair of tongues 16 struck forwardly therefrom and in alignment with the bearing tongues 11 and 12. The pivot rod 14 extends through the tongues 16 and is secured to said tongue 16 by soldering, welding or other suitable means. Thus the valve member 15 is held in position by the rod 14 and is permitted to swing with said rod to close or partially open the aperture defined by the rim 9. In order to give the valve 15 a greater range of swinging movement I provide cut-outs 17 in the valve member 15 so that said valve will not so quickly strike against the inner edge of the rim 9. However, after a certain degree of swing the

edges of the cut-outs 17 will engage the rim 9 to provide a limit stop for the valve.

While I have shown the cut-outs 17 in the valve member 15 they could, of course, be conveniently made in the rim 9 with the same function and effect.

In order to prevent the lower portion of the valve 15 from swinging outwardly I provide a stop in the form of a tongue 18 which is struck from the lower portion of the rim 9 and bent outwardly and upwardly against the face of the rim and inwardly beyond the inner edge of the rim to lie in the path of movement of the lower portion of the valve 15.

It will be seen from the foregoing that I have provided a draft regulator made up of three parts, a rim, a pivot pin, and a valve element. The rim includes integral means for rotatably positioning the regulator on the end of a short pipe section or T so that it can be twisted to various positions to alter the effective weight of the pivot valve. Said rim also includes integrally formed bearing members for the pivot pin or rod and it further includes an integrally formed stop member to limit swinging movement of the valve in one direction. The pivot pin is supported by the integrally formed bearing elements and it in turn is connected to the valve to support it for swinging movement. The structure is so greatly simplified that it can be manufactured at extremely low cost and its few separate parts make the matter of assembly extremely easy.

In Figs. 4 and 5 there is shown a slightly modified form of the invention, the difference lying in the arrangement of the pivot member. In that form it is shown to be a generally V-shaped element 19 which is welded or otherwise suitably secured to the valve member 15 and which has outwardly bent arm portions 20 which extend through the bearing member 12 as in the case of

the straight rod 14 in Figs. 1 through 3. The V-shaped pivot member 19 is offset as at 21 since the lower portion is flat against the valve 15 and the upper portion must be set out to coincide with the apertures in tongues 12. This construction provides more weight in the lower portion of the valve than in the case of the device shown in Figs. 1 through 3 since there is a considerable portion of the pivot member 19 below the pivotal axis of the valve. The remaining features of the device, however, are the same as those shown in the first embodiment.

While I have shown two forms of the invention it will, of course, be understood that various changes may be made in the form, arrangement, details and proportions of the various parts without departing from the scope of my invention.

What I claim is:

1. A draft regulator comprising, a pipe section having an outwardly directed flange thereon, an annular rim having tongues struck therefrom at spaced points to provide pipe flange engaging means, said rim also having apertured tongues struck therefrom to provide bearing elements, a pivot pin in the apertures of said bearing elements, stop means adjacent said bearing elements to limit axial movement of said pivot pin, and a valve member swingably supported in said rim by said pivot pin.

2. A draft regulator comprising, a rim, aligned oppositely disposed pairs of said tongues struck from and extending at right angles to the plane of said rim, the innermost of each pair of tongues having an aperture therein, pivot means extending through said apertured tongues, the outermost of said tongues restraining said pivot means against outward endwise movement, and a valve member mounted on said pivot means within said rim for swinging movement relative to said rim.

CLARENCE A. CROOKER.
